UNITED STATES PATENT OFFICE

2,269,477

APPARATUS AND METHOD FOR MODIFICATION OF FLOW OF AIR, GASES, AND THE LIKE

Herbert A. Reece, Cleveland Heights, Ohio, assignor to Meehanite Metal Corporation, a corporation of Tennessee

Application July 16, 1940, Serial No. 345,719

20 Claims. (Cl. 266—30)

My invention relates to supply apparatus for delivery of air and the like, such as wind boxes for metallurgical and other furnaces, and to the operation of the same.

My present invention, herein described, is related in subject matter to my invention described in my United States Letters Patent No. 2,197,947 issued on April 23, 1940, and to my invention described in my co-pending United States patent application, Serial No. 330,878, filed April 22, 1940, and is directed to the same and similar problems of furnace operation and control of air flow as is set forth in said issued patent and said co-pending application.

In the following discussion and description the operation and structure of a cupola for the remelting of metal will be referred to, but it is to be understood that my invention includes the structure and operation of all furnaces or similar devices wherein a blast of air or other gases is supplied through a plurality of tuyères or like openings to the interior of the furnace or similar device.

It is an object of my invention to provide a wind box for supplying an air blast at substantially equal velocities to each of a plurality of tuyères.

A further object is the provision of improved apparatus and method for supplying an air blast to each of several tuyères at desired velocities without disturbing the relative volume of air supplied to each of the several tuyères.

Another object is the control of the air blast delivered to a plurality of tuyères of a furnace from a wind box.

Another object is the modification of the current of air blast moving through a wind box.

Another object is the modification of the direction of portions of an air blast passing through a wind box from an inlet to a plurality of outlets.

Another object is the provision of apparatus and method of modifying a flow of air and like gases through a common distributing chamber.

Another object is the provision of improved apparatus and method for eliminating of "tangential" flow of air through a wind box.

Another object is the provision for utilizing the force of "tangential" flow of air moving through the wind box to provide a yieldable resistance to the flow of air moving through the wind box toward the tuyère entrances.

Another object is the provision for balancing "tangential" flow of air with longitudinal flow of air to equalize said flow of air supplied to a plurality of tuyères from a wind box.

Another object is the provision for equalizing the flow of air through a common distributing chamber by resisting members movable by the flow of air.

5 Another object is the provision for counter-balancing a resistance to air flow with a yielding to the air flow in a manner to equalize the velocity of the air flow in different localities of the wind box to supply the air to the outlets of the wind box at uniform velocity.

Other objects and a fuller understanding of my invention may be had by referring to the following description and claims, taken in conjunction with the accompanying drawings, in which:

15 Figure 1 is an elevational view of a wind box mounted upon a cupola;

Figure 2 is a cross-sectional view taken lengthwise of the cupola and wind box shown in Figure 1;

20 Figure 3 is a transverse cross-sectional view taken through the line 3—3 of Figure 2;

Figure 4 is an enlarged detailed view of a revolvable vane member mounted within the wind box as shown in Figures 2 and 3;

25 Figure 5 is an endwise view of the revolvable vane member shown in Figure 4 as viewed in the direction of the arrows 5—5 of Figure 4;

Figure 6 illustrates a modified form of revolvable vane member in which the vanes are spirally disposed;

30 Figure 7 is an endwise view of the vane members shown in Figure 6 as viewing the vane member in the direction of the arrows 7—7 of Figure 6;

35 Figure 8 is a view of a modified form of apparatus in which the several vane members are not connected together to operate in unison; and

40 Figure 9 is a view largely diagrammatical in nature to illustrate the cooperative relationship of the parts of the apparatus and is a view of the wind box laid out in the flat upon opening of the wind box along a longitudinal seam, the figure showing the view as seen from the inside 45 of the furnace.

Inasmuch as the invention disclosed herein is directed to the wind box and the portion of the cupola adjacent thereto it has not been considered necessary to show all parts of the cupola and therefore the drawings do not include the top portion and the bottom portion of the cupola, which portions may be considered as having the usual form. Also, for purposes of simplicity in illustration, the usual tap hole and slag hole are not shown. It has also been considered unneces-

sary to illustrate such other openings as a clean-out door, breast arch, or drop-bottom doors. The cupola with which the invention is associated and which is described herein may be considered, however, as having all of the parts necessary for the usual operation of the same.

As shown in the several views of the drawings the cupola body or shell 21 is in the form of a cylindrical shaft, the inner walls of the cupola body 21 being lined by the fire brick lining 24. The body 21 and the lining 24 are mounted upon the usual bottom plate and thereby forming the enclosed shaft of the cupola.

A wind box 22 of cylindrical shape is mounted upon the cupola body 21 by welding or other suitable means and in the embodiment shown, the outer wall of the cupola body forms one of the enclosing walls of the wind box 22. It is therefore seen from the views of the drawings that the wind box 22 forms an enclosed jacket surrounding the cupola body 21 in such a way that air introduced into the wind box may circulate entirely around the cupola body.

The inlet conduit 23 is in communication with the air blower or other source of an air blast (not shown) and the inlet conduit 23 is connected to the wind box 22 at the upper portion of the wind box 22 so as to afford communication between the air blower and the inlet opening 25 of the wind box 22.

In the cupola illustrated there are six tuyères extending through the wall and lining of the cupola body 21 to establish communication between the interior of the shaft of the cupola and the wind box 22. Tuyères 30, 31 and 32 as seen from the inside of the shaft of the cupola are illustrated in Figure 2. All six tuyères, 30, 31, 32, 33, 34 and 35 are shown in dotted lines in Figure 3 and are also illustrated in Figure 9. These tuyères are of substantially equal size and are uniformly spaced around the periphery of the cupola. It is to be noted that the tuyères enter the cupola body at a low level in the cupola and communicate with the wind box in a lower portion thereof. In order that the operator may look into the tuyères from the outside of the furnace, peep holes are provided in the wind box opposite each of the tuyères and mica or other suitable substance is sealed over these keep holes. Except when necessary, keep hole covers 28 hingedly connected to the wind box 22 are kept in position over the keep holes by means of the latch members 29.

The arrangement of the wind box, the inlet and the outlets to the tuyères is such that without my control apparatus the blast of air entering the wind box 22 from the inlet 25 circles around the interior of the wind box in substantially one circumferential direction, the air so moving in currents of unequal velocity. The air blast thus moving through the wind box would be supplied to the tuyères at unequal velocities in the absence of adequate control of the flow of air. The air circulating around the wind box tends to flow tangentially of the entrances of the tuyères and for this reason this circular flow of air is generally referred to in the art as a "tangential" flow. Without adequate control of such "tangential" flow of air and of the velocity of the currents of air it is found that the air is supplied to the tuyères at unequal velocities resulting in improper furnace operation. By the control of the flow of air through the wind box in the manner here described the velocity of the air is modified to provide a sup-

ply of air to the plurality of tuyères at substantially equal velocity, the circulatory and "tangential" flow of air being transformed into a vertical flow of uniform density and equal velocity to the tuyère entrances.

With reference to the views of the drawings there is shown positioned within the wind box below, and at a distance from, the inlet opening 25 a plurality of vane members comprising vanes 38 radiating outwardly from the plurality of shafts 37. The shafts 37 are journaled to the walls of the wind box 22 by being rotatively mounted within openings 39 and 40 formed in the walls of the wind box. The vanes 38 radiating outwardly from the shafts 37 are evenly spaced from each other as is shown in Figure 5. As the interior of the wind box is annular in shape it is preferable to have the vane members constructed with the diameter at one end larger than the diameter at the other end, the larger end of the vane member being positioned adjacent the outer wall of the wind box and the smaller end of the vane member being positioned adjacent the inner wall of the wind box. By the use of such wedge-shaped vane members in the cross-sectional area of the wind box at the plane of the axial shafts 37 is substantially filled with the vane members, leaving only a minimum of open space not blocked by the vane members. Also, by having the larger diameter end of the vane members somewhat curved to complement the inner wall of the wind box 22, as better shown in Figure 4, the interior cross-sectional area of the wind box is more effectively filled or blocked. As is shown in Figure 3 the plurality of vane members made up of the vanes 38 extending from the axial shaft 37 substantially fill the cross-sectional area of the wind box and thus substantially forms a movable obstruction dividing the upper portion of the wind box from the lower portion of the wind box.

The shafts 37 which form the axes for the vanes 38 extend radially out from the furnace and are disposed in one plane transversely of the wind box. Air moving through the wind box from the inlet 25 to the plurality of tuyère entrances encounters the vane members. The vanes 38 are extended in a gradual curve or are "cupped" as they radiate from the shafts 37. By this form of the vanes the force of the air blast upon the upper half of the several vane members tends to revolve the vane members in one direction. As is more apparent in the end view of a vane member shown in Figure 5, the air blast tends to "catch" in the upwardly curved vanes on the right side of Figure 5 and thus tending to cause the vane member shown in Figure 5 to revolve in a clockwise direction.

Non-rotatively secured to the outer end of each shaft 37 extended outwardly of the wind box 22 is a gear 41. As the radiating vanes 38 are rigidly secured to the shaft 37 the revolution of the vanes 38 causes the simultaneous rotation of the gears 41. A large ring gear 42 completely encircling the wind box 22 has gear teeth formed in its lower edge which enmesh with the teeth of the gears 41. Therefore, rotation of the gears 41 causes the revolution of the ring gear 42 around the wind box, the gears 41 and the ring 42 being thereby synchronized to move in unison.

The upper edge of the ring gear 42 has ratchet teeth 43 formed thereon and one or more pawls 44 pivotally secured to the wall of the wind box engage the ratchet teeth 43 in such manner as to permit the ring gear 42 to revolve in one direc-

tion and to prevent it to revolve in the opposite direction. The spring 45 connecting the pawl 44 with the wall of the wind box urges the pawl 44 into engagement with the ratchet teeth 43 and also provides a retarding action to the revolution of the ring gear 42 and hence the rotation of the gears 41. The friction of the parts and the yieldable resistance of the spring 45 provides a retarding action or "drag" upon the rotation of the shafts 37 and the revolution of the vanes 38 thereon.

To prevent the locking or jamming of the ring gear 42 and the gears 41 there is provided an annular bearing support 48 which is secured by welding or other suitable means to the outer wall 15 of the wind box. Rollers 47 rotatively mounted on pins 46 extending inwardly from the ring gear 42 roll upon and are supported by the bearing support 48. In this manner the weight of the ring gear 42 is borne by the annular support 48 rather than upon the gears 41. The ring gear 42 circles around and around the wind box upon the track formed by the support 48 upon the rotation of the gears 41 enmeshed therewith.

The respective vane members are mounted within the wind box in such manner that they rotate in a direction opposite from the circulatory or "tangential" flow of the air blast in the upper portion of the wind box. This relationship of the direction of rotation of the vane members relative to the direction of the air blast in the upper part of the wind box is better illustrated by the diagrammatical view of Figure 9. As indicated by the upper arrows the air blast entering the wind box from the inlet 25 moves from the left to the right. This same direction of flow of the air blast would be considered as a flow in a clockwise direction in the cross-sectional view of Figure 3. As has been explained, it is desirable to "break up" or diffuse this circulatory or "tangential" flow of air comprising currents of unequal velocity. If the vane members were positioned to revolve in the same general direction as the direction of the "tangential" flow some of the force of the "tangential" flow would tend to carry over into the lower portion of the wind box. However, by having the vane members revolve in such a direction as to oppose the undesired "tangential" flow the movement of the air from the upper portion of the wind box to the lower portion of the wind box will be made independently of the force of this "tangential" flow. In Figure 9 as the "tangential" flow is indicated as moving from left to right, the revolution of the vane members is in a counterclockwise direction as indicated by the curved arrows.

The curving disposition of the vanes 38 comprising each vane member is therefore such that downward movement of the air blast tends to rotate the vane members in a single-clockwise direction. Also, by means of the ring gear 42 moving in only one direction (by means of the ratchet teeth 43 and pawl 44) the vane members are permitted to revolve in only one direction, which in the view of Figure 9 would be in a counter-clockwise direction. Therefore, not only by the shape of the vanes 38 but also by the positive limitation means afforded by the ratchet and pawl on the ring gear, are the vane members prevented from revolving in the same general direction as the "tangential" flow of air in the upper portion of the wind box.

Insofar as the flow of air in the upper portion of the wind box is tangential, it will tend to prevent the vane members from revolving in said

counter-clockwise direction and thus tend to resist the downward flow of the air blast. It is therefore seen that the tangential force tends to urge the vane members against revolving in the direction they otherwise would be permitted to revolve and thus somewhat counter-balances the downward force of the air blast causing the vane members to revolve. The force of the air blast brought into the upper portion of the wind box, however, causes the vane members to yield to the force thereof, to revolve in the direction permitted and to permit the air to thus pass downwardly from the upper portion of the wind box to the lower portion of the wind box. By this arrangement the force of the tangential flow tends to yieldably urge the vane members against rotation while the dominant pressure of the downwardly moving air blast overcomes the yieldable resistance of the vane members to permit the air to flow downwardly at modified velocity. This yieldable resistance offered by the force of the tangential flow is in addition to the yieldable resistance which would otherwise be offered by the revolvable vane members by reason of friction of the parts, the spring pressed pawl, and the inherent resistance to the flow of air offered by the shape and disposition of the vane members.

By means of the yieldable resistance of the vanes 38 to the flow of air the velocity of the air flow through the wind box is modified and is brought into equilibrium in all locations throughout the cross-sectional area of the wind box. As the vane members are substantially evenly distributed around the wind box and are of substantially the same size and subject to the same retarding action, there is a modification of the air flow in substantially the same way by all of the vane members. In addition, the connecting means provided by the ring gear tying in together all of the revolving vane members assist in the distribution of the air flow to substantially equalize the velocity of all portions of the air flow passing from the upper portion of the wind box to the lower portion of the wind box. The described apparatus so modifies the velocity of the air flow and corrects the undesired tangential flow that the air is supplied to the plurality of tuyère openings in the lower portion of the wind box at substantially equal velocity.

In Figures 6 and 7 there is illustrated a modified form of vane member in which the vanes are spirally disposed relative to the shafts 37 about which they revolve. The disposition of the spirally disposed vanes 50 is such that the vanes meet the force of the air blast at a compound angle. The general operation of the vane members having the spiral vanes 50 is similar in principle to that of the vane members having the straight slided vanes 38, the vane members with the spiral vanes taking on some of the characteristics of a turbine.

In Figure 8 there is a modified form of arrangement illustrated wherein each vane member is independent of the operation of the other vane members, the use of the ring gear 42 connecting the vane members being eliminated. A ratchet wheel 52 non-rotatively secured to the outer end of the shaft 37 takes the place of the gear 41 shown in Figures 2 and 4. A pawl 53 pivotally secured to the wall of the wind box 22 and held down in ratchet engagement with the ratchet wheel 52 by means of the spring 54 provides a yieldable resistance to rotation of the shafts 37 and permits the shafts 37 to rotate in only one direction. In the view of Figure 8 the vane mem-

ber would revolve in a clockwise direction as indicated by the curved arrow and the tangential flow would be from right to left as indicated by the upper arrow. The plurality of independently operated vane members mounted as in Figure 8 break up the force of the tangential flow and modify the velocity of the air flow moving from the upper portion of the wind box to the lower portion of the wind box. As the modifying force of each vane member would be approximately the same, the velocity of the air blast would tend to equalize. Although there is a desirable modification of the velocity of the air blast and a correction of the tangential flow it is preferable to have the vane members operatively connected together such as in the manner shown in Figures 1, 2 and 3 as giving more efficient results in equalization of the velocity of the air blast delivered to the tuyère entrances.

The results obtainable by the use of the apparatus and method of air control herein described greatly increases the efficiency in the operation of furnaces. The description and disclosure herein made will at once suggest other forms and arrangements in the carrying out of the described invention but such other forms, arrangements and adaptations are included within the teaching of the discovery and invention herein disclosed by the drawings and description.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In a furnace having a wind box for supplying a blast of air to a plurality of tuyères, said wind box having an inlet adapted to communicate with a source of an air blast and having outlets in communication with said tuyères, a plurality of revolvable vane members positioned in said wind box intermediate of, and at a distance from, said inlet and said outlets and in the path of the air blast passing through the wind box, said vane members having radially extending vanes revolvable on substantially horizontally disposed axes, said vane members resisting said air blast and yielding thereto to revolve on said axes, respectively, the air blast revolving said vane members being modified in velocity to be supplied to said outlets at said modified velocity.

2. In a furnace having a wind box for supplying a blast of air to a plurality of tuyères, said wind box having an inlet adapted to communicate with a source of an air blast and having outlets in communication with said tuyères, a plurality of revolvable vane members positioned around said wind box in the path of the said air blast passing through the wind box from the inlet to said outlets to divide the wind box into a portion adjacent the said inlet and another portion adjacent the said outlets, said vane members having axes disposed radially of said furnace and being revolvable by the force of said air blast, the vane members providing a resistance to said air blast yieldable upon revolution of the vane members to modify the velocity of the air blast passing to said another portion of the wind box adjacent said outlets.

3. In a furnace having a wind box for supplying a blast of air to a plurality of tuyères, said

wind box having an inlet adapted to communicate with a source of an air blast and having outlets in communication with said tuyères, a plurality of revolvable vane members positioned in said wind box intermediate a portion of the wind box adjacent said inlet and another portion of the wind box adjacent said outlets, the axes of the revolvable vane members being disposed substantially radially of the furnace and being distributed substantially uniformly around the wind box, said revolvable vane members providing a resistance to said air blast and revolving under the force of the air blast to modify the velocity thereof, the air blast revolving said vane members and passing to said another portion of the wind box being supplied to said outlets at said modified velocity.

4. In a furnace having a wind box for supplying a blast of air to the entrances of a plurality of tuyères communicating with said furnace, said wind box having an inlet adapted to communicate with a source of an air blast, a plurality of vane members positioned in said wind box to substantially separate the wind box into a portion adjacent said inlet and another portion adjacent said entrances, said vane members having axes journaled to said wind box and disposed substantially radially of the furnace, the vane members having vanes extending radially from said axes, said vanes recurrently meeting and resisting said air blast and yielding thereto to revolve on said axes, the recurrent resistance and yieldance by the revolvable vanes modifying the velocity of said air blast supplied to said entrances from another portion of the wind box.

5. In a furnace having a wind box positioned around the body of the furnace for supplying a blast of air to the entrances of a plurality of tuyères communicating with said furnace, said wind box having an inlet adapted to communicate with a source of an air blast, an obstruction mounted within the wind box to divide the wind box into a portion adjacent said inlet and a portion adjacent said outlets, said obstruction comprising a plurality of vanes radiating from a plurality of axes disposed radially of said furnace and distributed around said wind box, said vanes being revolvable about said axes recurrently to resist, and to yield to, said air blast, the air blast meeting and revolving said vanes being modified to be supplied at substantially equal velocities to said tuyère entrances.

6. In a furnace having a wind box for supplying a blast of air to a plurality of tuyères, said wind box having an inlet adapted to communicate with a source of an air blast and having outlets in communication with said tuyères, a plurality of vane members positioned in said wind box intermediate of, and at a distance from, said inlet and said outlets dividing the wind box into adjacent portions, said vane members having axes journaled on said wind box and disposed radially of the furnace at intervals around the wind box, said vane members having vanes extended from said axes and disposed recurrently to meet, and to be revolved about said axes by, said air blast passing through the wind box, said vanes successively yieldably resisting said air blast in revolving about said axes, the yieldable resistance of said vanes modifying the velocity of said air blast delivered to said outlets.

7. In a furnace having a wind box for supplying a blast of air to a plurality of tuyères, said

wind box having an inlet adapted to communicate with a source of an air blast and having outlets in communication with said tuyères, a plurality of movable resistors positioned in said wind box intermediate of, and at a distance from, said inlet and said outlets and in the path of the air blast passing through the wind box, said movable resistors being revoluble about axes disposed radially of said furnace at intervals around said wind box, said movable resistors extending substantially throughout the cross-sectional area of the wind box substantially to separate the portion of the wind box adjacent the inlet and the portion of the wind box adjacent the outlets, the revolution of said movable resistors by the force of said air blast recurrently moving said resistors into the path of said air blast to yieldably resist the same, the recurrent resistance provided by said resistors modifying the velocity of the air blast supplied to said outlets from the wind box.

8. In a furnace having a wind box for supplying a blast of air to a plurality of tuyères entering the furnace, said wind box having an inlet adapted to communicate with a source of an air blast and having outlets in communication with said tuyères, an obstruction positioned in said wind box intermediate the inlet and the outlets for resisting the flow of air through the wind box toward the outlets, said obstruction including a plurality of movable members arranged in groups radiating from a plurality of axes disposed transversely of said wind box, said movable members being adapted to revolve about said axes and to recurrently pass through the plane of said plurality of axes, the said movable members in said plane resisting said air blast and revolving to a position away from said plane in yieldance to the force of said air blast, the revolvement of said movable members providing for the recurrent yieldable resistance of said movable members to the air blast to provide for the modification of the velocity of the air blast supplied to said outlets.

9. In a furnace having a wind box positioned around the body of the furnace for supplying air to a plurality of tuyères entering the furnace, said wind box having an inlet adapted to communicate with a source of an air blast and having outlets in communication with said tuyères, the arrangement of the wind box, inlet and outlets being such that currents of air of unequal velocities circulate and move through the wind box, an obstruction positioned in said wind box to divide the wind box into a portion adjacent the inlet and a portion adjacent the outlets, said obstruction comprising a plurality of vanes arranged in groups radiating from axes disposed radially of, and distributed around, said furnace, said vanes resisting said currents of air circulating around the wind box to modify the velocity thereof, the air moving through the wind box from the inlet to the outlets revolving said vanes about said axes into position recurrently to meet and resist said currents of air, the revolution of said vanes providing for the successive disposition of said vanes in the plane of the said obstruction and the successive yielding of the vanes to the force of the air blast to modify the velocity of the air blast supplied to said outlets.

10. In a furnace having a wind box positioned around the body of the furnace for supplying air to a plurality of tuyères entering the furnace, said wind box having an inlet adapted to communicate with a source of an air blast and having

outlets in communication with said tuyères, the arrangement of the wind box, inlet and outlets being such that the blast of air entering the wind box from the inlet circles around within the wind box in one circumferential direction, the combination of a plurality of vane members positioned in said wind box intermediate of, and at a distance from, said inlet and said outlets to divide the wind box into a portion adjacent the inlet and a portion adjacent the outlets, the vane members being revoluble by said air blast on axes disposed substantially radially of the furnace and distributed around the wind box, and means for limiting the revolutions of said vane members to revolvement in a direction opposed to said circumferential direction of the air blast, said vane members providing a yieldable resistance to the air blast moving from the portion of the wind box adjacent the inlet to the portion of the wind box adjacent the outlets to modify the direction and velocity of the air blast supplied to said outlets.

11. In a furnace having a wind box positioned around the body of the furnace for supplying air to a plurality of tuyères entering the furnace, said wind box having an inlet adapted to communicate with a source of an air blast and having outlets in communication with said tuyères, the arrangement of the wind box, inlet and outlets being such that the blast of air entering the wind box from the inlet circles around within the wind box in one circumferential direction, the combination of a plurality of vane members positioned in said wind box intermediate of, and at a distance from, said inlet and said outlets to divide the wind box into a portion adjacent the inlet and a portion adjacent the outlets, the vane members being revoluble by said air blast on axes disposed substantially radially of the furnace and distributed around the wind box, retarding means for retarding the revolutions of said vane members in resistance to said air blast, and means for limiting the revolutions of said vane members to revolvement in a direction opposed to said circumferential direction of the air blast, said vane members providing a yieldable resistance to the air blast moving from the portion of the wind box adjacent the inlet to the portion of the wind box adjacent the outlets to modify the direction and velocity of the air blast supplied to said outlets.

12. In a furnace having a wind box positioned around the body of the furnace for supplying air to a plurality of tuyères entering the furnace, said wind box having an inlet adapted to communicate with a source of an air blast and having outlets in communication with said tuyères, the arrangement of the wind box, inlet and outlets being such that the blast of air entering the wind box from the inlet circles around within the wind box in one circumferential direction, the combination of a plurality of vane members positioned in said wind box intermediate of, and at a distance from, said inlet and said outlets to divide the wind box into a portion adjacent the inlet and a portion adjacent the outlets, the vane members being revoluble by said air blast on axes disposed substantially radially of the furnace and distributed around the wind box, retarding means for retarding the revolutions of said vane members in resistance to said air blast, connecting means operatively connecting said vane members to synchronize the revolutions thereof in unison, and means for limiting the revolutions of said

vane members to revolvement in a direction opposed to said circumferential direction of the air blast, said vane members providing a yieldable resistance to the air blast moving from the portion of the wind box adjacent the inlet to the portion of the wind box adjacent the outlets to modify the direction and velocity of the air blast supplied to said outlets.

13. In a furnace having a wind box forming a common distributing chamber for supplying a blast of air to the entrances of a plurality of tuyères communicating with said furnace, said wind box having an inlet adapted to communicate with a source of an air blast, air blast resisting means positioned in said wind box to divide the wind box into a portion adjacent said inlet and a portion adjacent said entrances, said resisting means including a plurality of vanes extending intermediate the walls of said wind box, said vanes being arranged in groups radiating from a plurality of axes extended in a plane disposed transversely of said wind box, said vanes being revolvable by said air blast on said axes to recurrently move in and out of said plane, the vanes in said plane yieldably resisting said air blast to modify the velocity thereof, the air blast being supplied to said tuyère entrances at said modified velocity.

14. In a furnace having a wind box positioned around the body of the furnace for supplying air to a plurality of tuyères entering the furnace, said wind box having an inlet adapted to communicate with a source of an air blast and having outlets in communication with said tuyères, the arrangement of the wind box, inlet and outlets being such that currents of air entering the wind box circulate around in one general circumferential direction, a plurality of revolvable vane members positioned in said wind box in a plane intermediate of, and at a distance from, the said inlet and said outlets, said vane members being revolvable by the force of said air blast to recurrently swing in and out of said plane, retarding means for retarding the revolution of the vane members, and means for limiting the revolution of said vane members to one direction, said vane members revolving to oppose said currents of air circulating in one circumferential direction and to yieldably resist the air blast passing through the wind box from the inlet to the outlets, said air blast supplied to said outlets being modified in direction and velocity by said vane members.

15. In a furnace having a wind box positioned around the body of the furnace for supplying air to a plurality of tuyères entering the furnace, said wind box having an inlet adapted to communicate with a source of an air blast and having outlets in communication with said tuyères, the arrangement of the wind box, inlet and outlets being such that currents of air entering the wind box circulate around in one general circumferential direction, a plurality of vane members positioned in said wind box intermediate of said inlet and said outlets, said vane members being revolvable on a plurality of axes disposed in a plane passing transversely of said wind box intermediate of, and at a distance from said inlet and said outlets, connecting means operatively connecting said vane members to synchronize the revolving thereof in unison, and ratchet means limiting the revolvement of the vane members to one rotative direction, said vane members being revolvable in opposition to said currents of air circulating around the wind box and in yieldable resistance to the air blast pass-

ing through the wind box to said outlets, the air blast being modified by said vane members to be supplied to said outlets at substantially equal velocity.

16. In a furnace having a wind box for supplying a blast of air to a plurality of tuyères, said wind box having an inlet adapted to communicate with a source of an air blast and having outlets in communication with said tuyères, the arrangement of the wind box, inlet and outlets being such that the air blast entering the wind box from the inlet flows tangentially of the furnace, a plurality of vanes positioned in said wind box intermediate of, and at a distance from, said inlet and said outlets and in the path of the air blast passing through the wind box, said vanes being arranged in groups radiating from a plurality of axes and being revolvable around said axes, said vanes being disposed to be urged to revolve in one direction by said tangential flow and to be urged to revolve in the opposite direction by the force of the air blast moving longitudinally of the wind box toward said outlets, said vanes being revolvable in only said opposite direction, the urging of the vanes in said one direction providing a yieldable resistance to the revolution in said opposite direction, said vanes providing a yieldable resistance to said blast of air moving toward the outlets to modify the velocity of the air blast supplied to said outlets.

17. In a furnace having a wind box for supplying a blast of air to a plurality of tuyères, said wind box having an inlet adapted to communicate with a source of an air blast and having outlets in communication with said tuyères, the arrangement of the wind box, inlet and outlets being such that the air blast entering the wind box from the inlet flows tangentially of the furnace, a plurality of vanes positioned in said wind box intermediate of, and at a distance from, said inlet and said outlets and in the path of the air blast passing through the wind box, said vanes being arranged to revolve about axes disposed substantially parallel to a plane passing through said outlets and a plane passing through said inlet, the vanes in revolving on said axes recurrently extending into the path of said tangential flow of air to resist the same, the said vanes being concavely formed to revolve, under the force of the air blast moving longitudinally of the wind box and toward the plane of the outlets, in a direction opposing the said tangential flow, said vanes yieldably urged in one direction by the tangential flow and yieldably revolving by the force of said longitudinal flow of air modifying the flow of air supplied to said outlets.

18. In a furnace having a wind box for supplying a blast of air to a plurality of tuyères, said wind box having an inlet adapted to communicate with a source of an air blast and having outlets in communication with said tuyères, the arrangement of the wind box, inlet and outlets being such that the air blast entering the wind box from the inlet flows tangentially of the furnace, a plurality of vanes positioned in said wind box intermediate of, and at a distance from, said inlet and said outlets and in the path of the air blast passing through the wind box, the said vanes being mounted to recurrently resist said tangential flow of air and to recurrently yield to the flow of air moving longitudinally of the wind box toward the outlets to move in opposition to the force of said tangential flow, the yieldable movement of said vanes in opposition to said resistance modifying the velocity of the air blast

moving through the wind box, and connecting means operatively connecting said vanes to move in unison, the modification of the velocity of the air blast by said plurality of vanes providing for the supply of air to said plurality of outlets at substantially equal velocities.

19. The method of controlling the flow of air supplied to a plurality of tuyères of a furnace, comprising: passing an air blast through a conduit, supplying the air blast through the conduit into an enlarged air chamber, resisting the tangential flow of air set up in said air chamber, resisting the flow of the air blast moving longitudinally of the air chamber at an angle to said tangential flow and from one portion of the air chamber to another, yielding said latter resistance in opposition to said first resistance, passing said air blast through said yielding resistance into said another portion of the air chamber, and supplying the air blast from said another portion of the wind box to said tuyères at velocities modified by said yieldable resistance.

20. In the operation of a furnace, the method of furnishing an air blast to a plurality of tuyères having predetermined volume capacities from a wind box wherein tangential flow of air currents are encountered, comprising: resisting said tangential flow of air in a first portion of the wind box, resisting the flow of air moving longitudinally of the wind box at an angle to said tangential flow and from said first portion of the wind box to a second portion of the wind box, yielding said latter resistance to permit the flow of air to said second portion of the wind box, opposing said yielding with the resistance to said tangential flow to provide a yieldable resistance to the flow of air from said first portion of the wind box to a second portion of the wind box in accordance with the force of said tangential flow, and supplying the air flow modified by said yieldable resistance to the plurality of tuyeres at substantially equal velocities.
